EDGAR E. GREVE, OF BELLEVUE, PENNSYLVANIA

DRIVE BUSHING FOR ROTARY DRILLING MACHINES

Application filed December 24, 1925. Serial No. 77,672.

My invention relates to improvements in rotary drilling machines and more particularly to a new and improved drive bushing employed in such machines for effecting an engagement between a rotatable driving member of such machines and a member commonly called a grief stem, the latter being secured to the upper end of a string of drilling tubing. The grief stems are usually non-circular in cross section and as heretofore used, are designed to engage flat fixed surfaces on the interior of the drive bushings; in operation the stem has a free longitudinal or vertical movement in the bushing.

In the operation of drilling and particularly when a very hard formation is encountered, considerable torsional strain is placed on the grief stem, this strain sometimes causes the stem to twist and bite or cut into or become engaged with the bushing. The hard formation will also at times, cause the drill string with the said grief stem to jump up and down, and if the grief stem is bent or caught in the bushing, this jumping movement will lift the bushing out of the drive ring or in some cases cause even more trouble.

Among the objects of the present invention are to provide means for reducing the friction between the drive or grief stem and the drive bushing; also to prevent the grief stem from bending in or being caught in the drive bushing; and to provide a drive bushing having yielding or movable contact members adapted to engage the sides of the drive stem when the parts are assembled in a rotary drilling machine.

Another object of the present invention is to provide a drive bushing of simple construction, and of such a character that it may be readily applied to grief stems of various formations having non-circular cross sections.

In the accompanying drawings, which illustrate applications of my invention,

Figure 1 is a top view of a drive bushing constructed in accordance with my invention having a square stem receiving opening;

Figure 2, a similar view showing the bushing formed with an opening designed to receive a grief stem of fluted form;

Figure 3, an elevational view of the bushing of the form of Fig. 1;

Figure 4, a part elevational and a part sectional view showing a portion of a rotary drilling machine and a grief stem, and showing the drive bushing connecting the grief stem and the drive ring of the rotary drilling machine;

Figure 5, a top view showing a modified form of drive bushing; in this form the bushing is shown as an integral structure; and

Figure 6, a horizontal sectional view, the section being taken on line VI—VI of Fig. 3.

As illustrated, the drive bushing may be formed in two halves as shown by the forms of Figs. 1 and 2, or as an integral member, the later form being shown by Fig. 5; in either form the bushing is provided with grief stem yielding or movable contacting members and has a central opening for the reception of the grief stem, the configuration of the opening being dependent on the shape of the non-circular grief stem employed.

In Fig. 4 of the drawings, I have shown the drive bushing in position in a rotary drilling machine and engaging a portion of a grief stem A. The rotary may be of any desired construction; as shown, it includes a rotatable member 5 having a gear ring 6 formed thereon; said gear ring is designed to cooperate with a gear wheel 7 carried on the end of a shaft 8. 9 designates the drive ring of the rotary and 10 a spider mounted therein and adapted to receive the drive bushing.

The drive bushing constituting my invention may be made, as above stated, in two or more parts, or as an integral structure. The bushing, designated generally as 11, preferably comprises a conical tapering body 12 and an upper flange 13 running entirely around the structure and adapted to be seated on the shouldered portion 14 of the spider 10. In all of the forms illustrated the bushing is provided with a central opening having the walls thereof shaped to receive non-circular grief stems, varying in contour; that is to say, the opening may be a square opening as shown in the form of Fig. 1, or it may be an irregularly shaped opening designed to re-

ceive, for example, a fluted grief stem as shown in the form of Fig. 2. In all of the constructions illustrated, I provide a plurality of movable contacting members for the bushing, said contacting members being in the form of a plurality of rollers arranged to engage the sides of the grief stem.

As shown by Fig. 1, 15 designates a number of rollers extending inwardly from the periphery of the bushing body, to near the center of the bushing structure, and 16 designates a series of long rollers arranged one above the other and at right angles with the rollers 15.

15 The short rollers 15 are arranged in four vertically extending rows, four of the rollers being in the same horizontal plane and arranged in the two part bushing so that they will project into the stem receiving opening B and engage two sides of the square grief stem A at a certain level. Other similar rollers 15 disposed in other horizontal planes are designed to engage corresponding faces on the grief stem at different levels, as will 20 be clearly understood.

25 The long rollers 16 are arranged in two vertically extending rows and in different horizontal planes, and like the rollers 15, project into the opening B in order to make contact with and engage opposite faces of the grief stem. The rollers 16 are positioned in vertically extending planes at right angles with the vertical planes of the rollers 15.

30 In the form of Fig. 2, the bushing is designed to receive a fluted grief stem, not shown, and in this construction I have shown a series of short rollers 15^a and a series of short rollers 16^a arranged to provide contacting members for all of the flat faces of a grief 35 stem of the contour stated.

40 In the integral bushing structure shown in Fig. 5, I provide two sets of contacting members or rollers 15^b and 16^b; these rollers 15^b and 16^b, owing to the fact that the bushing is in one piece instead of being a split bushing, may all be long rollers, i. e., rollers extending throughout the width of the opening B². The contacting members of this form 45 are arranged in vertically extending rows at right angles with each other and with the rollers of each row located in different horizontal planes, as in other forms shown.

50 The means shown for maintaining the respective movable contacting rollers in position in the roller receiving openings of the bushing include keys or pins 17 designed to be positioned in pockets or cutouts 18, formed in the bushing, and co-act with bosses 19.

55 20 designates grooves formed in the bushing for the purpose of enabling lubrication of the rollers.

60 What I claim is:—

65 1. A drive bushing for rotary well drilling machines having a central stem receiving opening, a plurality of drive stem engaging

70 roller contacting members mounted in the bushing and having portions thereof projected into the opening, and means for securing the contacting members in the bushing, said bushing being formed with roller receiving openings in which the rollers are disposed.

75 2. A drive bushing for rotary well drilling machines having a central stem receiving opening, two roller drive stem contacting members carried thereby and each having a portion thereof projected into the opening, one member arranged at right angles with the other member, said bushing being formed with roller receiving openings in which the rollers are disposed, and means for securing the contacting members in the roller receiving openings of the bushing.

80 3. A drive bushing for rotary well drilling machines having a central stem receiving opening, a series of roller drive stem contacting members arranged one above the other, a second series of roller drive stem contacting members arranged one above the other and at right angles with the first series, said contacting members having portions projected into the opening, and means for securing the contact members in the bushing.

85 4. A drive bushing for rotary well drilling machines having a central stem receiving opening and a plurality of roller receiving openings, two roller drive stem contacting members carried thereby in said roller receiving openings, and each having a portion thereof projected into the stem receiving opening, one member arranged at right angles with the other member, and means for securing the contacting members in the roller receiving openings of the bushing including a detachable pin entered in a pocket of the 90 bushing.

95 In testimony whereof I affix my signature.
EDGAR E. GRÈVE.
